UNITED STATES PATENT OFFICE.

CRIST H. STEVICK, OF ASTORIA, NEW YORK.

AUTOMATIC ELECTRIC GAS-Drip ALARM DEVICE.

1,121,416.

Specification of Letters Patent. Patented Dec. 15, 1914.

Application filed January 23, 1914. Serial No. 812,652.

To all whom it may concern:

Be it known that I, CRIST H. STEVICK, a citizen of the United States, and residing at Astoria, Long Island, in the county of Queens and State of New York, have invented certain new and useful Improvements in Automatic Electric Gas-Drip Alarm Devices, of which the following is a specification, such as will enable those skilled in the art to which it appertains to make and use the same.

This invention relates to apparatus or devices for automatically giving notice of the collection of condensation water in a gas pipe or drip cup, in order that the sealing of the drip cup and the consequent cutting off of the flow of gas therethrough may be prevented; and the object of the invention is to provide an improved apparatus or device of this class which is simple in construction, efficient in operation, and which may be conveniently applied wherever necessary, and with this and other objects in view, the invention consists in a device or apparatus of the class specified, constructed and operating as hereinafter described and claimed.

The invention is fully disclosed in the following specification, of which the accompanying drawing forms a part in which the separate parts of my improvement are designated by suitable reference characters, said drawing being a sectional side elevation of a device or apparatus involving my invention.

In the practice of my invention, I provide a drip cup *a* of the usual or any preferred construction and with the opposite sides of which, and preferably near the top thereof, the gas supply pipe or main *b* is connected. The cup *a* is provided in the bottom thereof with a discharge pipe *c* having a valve *c*², and the top thereof is provided with a cap, cover, or other suitable closure device *d* through which is passed a drip pipe *e* having a packing *e*², and the pipe *e* extends downwardly to within a few inches of the bottom of the drip cup. I also provide a drum, box, or casing, *f* composed of top and bottom parts *f*² and *f*³ between which is secured a diaphragm *f*⁴ composed of flexible material and which divides the drum *f* into top and bottom chambers *f*⁵ and *f*⁶, the bottom chamber *f*⁶ being, in the construction shown, of greater vertical dimensions than the top chamber *f*⁵, and the pipe *e* connects

with the bottom portion of the drum *f* at one side thereof and communicates with the chamber *f*⁶ and is provided with a valve *e*³. A discharge pipe *g* is connected with the bottom portion of the drum *f* and also communicates with the chamber *f*⁶, and this pipe has an upwardly directed extension *g*² having a small outlet orifice *g*³.

The drum *f* is provided in the top thereof with an aperture *f*⁷ closed by an insulated cap *h* of any suitable construction and through which is passed a vertically movable rod *i* which also passes through the aperture *f*⁷ and downwardly through the diaphragm *f*⁴ to which it is secured at *i*² in any desired manner. The cap *h* is provided on the top surface thereof with a raised annular contact flange or rim *h*² above which the rod *i* is provided with outwardly and downwardly directed spring contact devices *i*³, and electric circuit wires *j* and *j*² are connected with the top portion of the rod *i* at *i*³, and with the cap *h* at *j*², and the wires *j* and *j*² are also connected with a battery *k*, and placed in the circuit thus formed is an alarm device *m* preferably consisting of an ordinary electric bell.

In the operation of this apparatus, the valve *e*³ is open and by reason of the connection with the opposite sides of the cup *a* of the gas supply pipe or main *b*, as shown and described, the gas flows into and through said cup, as will be readily understood, and in this operation, the water of condensation that collects in the main flows into and collects in the bottom of the drip cup *a*, as shown at *n*. Under normal conditions, the gas will flow from the drip cup *a* through the pipe *e* and through the bottom chamber *f*⁶ of the drum *f* and through the pipe *g*, and a small amount of this gas will be discharged at *g*³ and may be ignited, if desired, and the light thus produced will show at all times that the said apparatus is in working order, and the amount of the water of condensation in the drip cup *a* is not sufficient to seal the flow of gas, or cut off the flow of gas through the pipe *e*. As the water of condensation gradually rises, however, in the bottom of the cup *a*, the lower end of the pipe *e* is sealed, and if this water is not discharged or pumped out, the flow of gas through said pipe *e* will be cut off, and the escape of gas from the drum *f* through the pipe *g* will reduce the pressure below the diaphragm *f*⁴, and the rod *i* will drop and

the contact device or devices i^3 will come in connection with the cap h , or the contact flange or rim h^2 thereof, and the circuit will be closed through the wires j and j^2 and battery k , and the alarm device m will be operated and notice will thus be given that the water of condensation must be removed from the drip cup a , and this may be accomplished by opening the valve c , or in any other manner.

The amount of the water of condensation in the bottom of the cup a , necessary to operate the apparatus as described, may be fixed at any desired amount by regulating the length of the pipe e , or the depth to which it extends into said cap, and while I have shown and described the preferred form and construction of my invention, it will be apparent that changes therein and modifications thereof may be made, within the scope of the appended claims, without departing from the spirit of my invention or sacrificing its advantages.

Having fully described my invention, what I claim as new and desire to secure by Letters Patent is:—

1. In a gas-drip alarm apparatus, a drip cup with which the gas supply main communicates at two points, a drip pipe passing downwardly through the top of said cup and terminating above the bottom thereof and adapted to be sealed by drip water as it rises in the bottom of said cup, and means whereby the sealing of said pipe will operate an alarm device.

2. In a gas-drip alarm apparatus, a drip cup with which the gas supply main communicates at two points, a drip pipe extending downwardly into said cup and terminating above the bottom thereof, a box having a horizontal flexible diaphragm forming top and bottom chambers therein and through the bottom portion of which the drip pipe communicates, said bottom portion of said box being also provided with a discharge pipe, and a rod vertically movable through the top part of said box and secured in said diaphragm, said rod forming

part of an open electric circuit adapted to be closed by the vertical movement thereof, and in which is placed an electric alarm device.

3. In an electric gas-drip alarm apparatus, a drip cup with the top portion of which a gas supply main communicates at two points, a drip pipe passing downwardly through the top of said cup and terminating above the bottom thereof, a box divided by a flexible horizontal diaphragm into top and bottom chambers and with the bottom portion of which said drip cup communicates, a discharge pipe also connected with the bottom portion of said box, a rod movable vertically through the top of said box and secured in said diaphragm, an open electric circuit of which said rod forms a part, and an electric alarm device placed in said circuit.

4. In a gas-drip alarm apparatus, a drip cup with which the gas supply main communicates at two points, a box divided horizontally by a flexible diaphragm into top and bottom chambers, a rod movable vertically through the top of said box and secured in said diaphragm, and means whereby the rise of drip water in said cup will operate said diaphragm and said rod to close an electric circuit in which is placed an electric alarm device.

5. In a gas-drip alarm apparatus, a drip cup with which the gas supply main communicates at two points, a drip pipe passing into the top portion of said cup and terminating above the bottom thereof and adapted to be sealed by drip water as it rises in the bottom of said cup, and means whereby the sealing of said part will operate an alarm device.

In testimony that I claim the foregoing as my invention I have signed my name in presence of the subscribing witnesses this 21st day of January 1914.

CRIST H. STEVICK.
